JAMES HALL TAYLOR, OF OAK PARK, ILLINOIS.

MACHINE FOR SHAPING PIPES.

Application filed March 6, 1925. Serial No. 13,651.

The invention relates to machines for forming flanges and other shapes on pipes.

One object of the invention is to provide an improved machine in which the pipe is internally and externally supported adjacent the end being shaped, so that irregular deformation will be prevented and the shaping will be localized to the point or points desired.

10 Another object of the invention is to provide an improved machine of this type in which the pipe is supported and driven through a chuck adjacent one of its ends and an internal grip at the other end at 15 which the shaping mechanism is located, so that the pipe will be driven at both ends. This is advantageous when the pipe is thin, so that deformation by torsional stresses is impossible.

20 Another object of the invention is to provide an improved machine in which the supporting head for the chuck at the end of the pipe which is remote from the shaping mechanism is quickly adjustable so the machine can be set to operate on pipes of different lengths and so as to avoid the necessity of adjusting the supporting mechanism for the pipe adjacent the shaping mechanism.

30 Another object of the invention is to provide means for uniformly and conjointly adjusting the supporting rollers for the end of the pipe which is being shaped.

Another object of the invention is to provide for longitudinal adjustment of the internal chuck adjacent the end of the pipe which is to be shaped to adapt it to hold the pipe for different kinds of shaping, such as flanging or corrugating.

40 Another object of the invention is to provide quickly-operable means to effect cross adjustment of the carriage which carries the shaping mechanism, to bring it into and out of its operative position, so that the pipe may be loaded into the machine from the end at which the shaping is done.

Another object of the invention is to provide improved mechanism for operating by power the mechanism for shifting the shaping roll carriage.

Other objects of the invention will appear from the specification.

The invention consists in the several novel features hereinafter set forth and more particularly defined by claims at the conclusion hereof.

In the drawings: Fig. 1 is a longitudinal section of a machine embodying the invention. Fig. 2 is a front elevation. Fig. 3 is a side elevation, parts being broken away. 60 Fig. 4 is a horizontal section. Fig. 5 is a longitudinal section through a portion of the pipe driving shaft and the parts connected thereto. Fig. 6 is a section on line 6-6 of Fig. 5. Fig. 7 is a section on line 65 7-7 of Fig. 5. Fig. 8 is a plan of the pipe shaping mechanism and its supporting means. Fig. 9 is a detail of the internal chuck for gripping the pipe adjacent the end at which it is shaped. Fig. 10 is a view 70 similar to Fig. 8, the shaping rolls being shown in a different position, parts being removed for illustrative purposes. Fig. 11 is a transverse section through the transversely adjustable carriage on which the 75 shaping mechanism is mounted. Fig. 12 is a section on line 12-12 of Fig. 8.

The invention is exemplified in a machine which comprises a series of rollers *a* for externally supporting a length of pipe to be 80 shaped adjacent the shaping mechanism; a chuck *b* for internally gripping and supporting the same end of the pipe and adjacent the rolls *a*; and a chuck *c* for supporting the other end of the pipe. An important feature of the invention consists in internally and externally supporting the pipe at the end which is being shaped so as to prevent irregular deformation of the metal and to localize the shaping or bending of 90 the metal to the portions or points desired. The pipe *d*, which is to be shaped, is insertable into the machine from the end at which the shaping mechanism is located and the chuck *c* is longitudinally adjustable to and 95 from the internal chuck and rollers *a* to adapt the machine for shaping pipes of different lengths without longitudinally shifting the rollers *a* and the internal chuck.

The chuck *c* comprises a head 22; jaws 23 which are radially slidable in channels 24 in the head 22, are radially adjustable by screw-shafts 24^a which are suitably journalled against endwise movement in the head 22, and are provided at the outer ends with 100 terminals 25 adapted for the application of a turning tool; pinions 26 fixed to the inner ends of shafts 24^a respectively; and a gear 27 for effecting conjoint and uniform adjustment of the shafts 24^a, so that the 105 jaws 23 will be equidistantly moved to or from the axis of the pipe *d*. The internal

5 chuck *b* comprises a head 28, which is fixedly secured to the shaft *e*, and jaws 29 which are radially slidable in the head and are adapted to grip the inner periphery of 10 the pipe *d*. Jaws 29 are radially shiftable into and out of engagement with the pipe by wedge members 30 fixed to the jaws and a wedge-head 31 which is axially movable relatively to the jaws and fixed to a longitudinally movable shaft 32. Shaft 32 extends longitudinally through shaft *e* and is fixedly connected to a piston 33 which is 15 slidable in a cylinder 34 and is adapted to be operated to adjust the internal chuck by fluid under pressure admitted to the cylinder 34. The latter is fixed to the outer end of shaft *e* so that it and shaft 32 will rotate with shaft *e*.

20 Shaft *e* extends rearwardly through and beyond chuck *b* and is supported at its rear end by a bracket 35. Shaft *e* is driven by a gear 36 which may be driven by any suitable mechanism, as well understood in the art. Said shaft extends through the sleeve, 25 which is journalled in the bearing 38. A key on sleeve 37 extends into a longitudinal key-way *e'*, so that the driving relation between them will be maintained while the sleeve is adjusted to different positions along 30 the shaft. Said bearing 38 is provided with laterally projecting studs or pintles 39 which are mounted in a bracket 40. To adapt the machine for pipes of different lengths, mechanism is provided for longitudinally adjusting the chuck *c* relatively to 35 the chuck *b* and rollers *a* and to facilitate the adjustment, motor-driven mechanism is provided. For this purpose, the supporting bracket 40, which is formed of sections secured together by bolts 41, is fixedly secured to a carriage 42 which is formed with shoes 43 adapted to slide on four rails 44. An electric motor 45 is mounted on an extension of the carriage 42 to operate the gearing for longitudinally shifting the carriage to adjust the chuck *c*. This gearing comprises a pinion 46 on the motor shaft; a gear 47 meshing with pinion 46 and fixed to a cross shaft 48, which is mounted in bearings 49 45 mounted in the carriage 42; a worm 50 on shaft 48; a worm-wheel 51 driven by worm 50 and fixed to a cross-shaft 52 which is journalled in bearings 53 on the carriage; pinions 54, keyed to shaft 52, pinions 55, meshing with 50 pinions 54 respectively and mounted on stub-shafts 56, which are mounted in the carriage 42, and gear racks 57 with which pinions 55 mesh respectively. A rack 57 is provided between each pair of rails 44. Worm 50 is 55 enclosed in a housing 58 formed in the carriage 42 and worm-gear 51 is also enclosed in said housing and in a semicylindrical housing section 59 which is removably secured to the carriage. Motor 45 is of the reversible type so that it may be operated in either

direction to drive the gearing to speedily shift the chuck *c* longitudinally of the machine to adapt it for shaping pipes of different lengths.

The rear end of shaft *e* is secured by a 70 key 61 to rotate with a sleeve 60 which is journalled and held against endwise movement in a bearing 62 which is provided with laterally projecting studs 62^a which are pivotally held in bracket 35. The purpose in 75 pivotally supporting the shaft *e* by means of studs 39 on bearing 38 and studs 62^a on bearing 60 is to make it possible to correctly align or position the chuck *b*, which is at the front end of the shaft, without cramping the 80 shaft in its bearings or causing undue wear.

In performing different shaping operations on the front end of the pipe, for example, such as shaping and corrugating, it is sometimes necessary to longitudinally adjust 85 the internal chuck *b* relatively to the stationary supporting rollers *a*, and for this purpose shaft *e* is longitudinally adjustable in sleeve 60. Said shaft is provided with a screw-thread 63 and a nut 64 on said thread 90 and also with a screw thread 65 with a nut 66 thereon. The shaft *e* is slideable in sleeve 60, and, by adjusting the nuts 64, 66, the entire shaft may be adjusted longitudinally. Key 61 is adapted to slide in a key-way in 95 sleeve 60. Gear 36 is keyed to said sleeve. The driving connection between gear 36 and shaft *e* is maintained in its different adjustments.

The rollers *a* are radially adjustable to 100 adapt them for supporting and rotatably guiding pipes of different diameters and to shift them into and out of operative position to permit placement and removal of the pipe into its operative position from the front of the machine. These rollers and the mechanism for supporting and shifting them are mounted in a frame *F* which is composed of upright I-beams 67 which have their lower ends fixedly secured and embedded in the machine base and plates 68 secured to said beams so as to form an approximately rectangular rigid supporting structure. The four rollers *a* are provided to support the pipes 90° apart. Each roller *a* is mounted 105 on a shaft 70 which is carried by a slide 71. Each slide 71 is slideable radially in a guide 72 which is formed of members fixed to the frame *F*. Each slide is radially movable by means of a screw-shaft 73 which is threaded to the guide and has its outer end held against longitudinal movement in a bearing 74. A bevelled pinion 75 is fixed to the outer end of each shaft 73. These shafts 73 are 110 geared together for conjoint adjustment to uniformly shift the rollers *a* by means of connecting shafts 76 with a bevelled pinion 77 at either end for meshing with pinions 75. Two of the shafts 76 extend vertically between the upper and lower screw-shafts and 115

another of the connecting shafts extends horizontally between the pinions 75 on the upper shafts 73. Said horizontal shaft 76 is mounted in bearings 77^a carried by the 5 frame. In practice, it is desirable to operate the rollers *a* quickly to facilitate the operation of the machine and for this purpose a reversible electric motor 78 is mounted on top of the frame F and is provided with a 10 pinion 79 which meshes with a gear 80 on said shaft 76. This exemplifies motor-driven mechanism for conjointly and equidistantly in radial direction, adjusting the rollers *a* in the stationary frame F.

15 A pair of rolls *g*, *g'*, adapted to engage the inner and outer peripheries of the front end of the pipe *d*, which are adapted to swing horizontally to form a flange on the pipe, exemplify means for shaping the pipe. 20 These rolls are mounted in an arcuate slide 81 which fits and is held in a corresponding 25 arcuate guide casing 82. Roll *g* is journaled on a stud 83 which is fixed in slide 81. Roll *g'* is sustained so it may be shifted to and from roll *g*, being carried by a stud 84 which is held in a slide 85 and a cap 86. A screw 87, operable by the hand wheel is held against longitudinal movement in cap 86 and extends through the slide 85 to shift 30 the roll *g'* into and out of operative relation with the roll *g*, so that pipes of different thicknesses may be grasped and shaped by these rolls.

Casing 82 is integrally formed with a 35 frame 90 to serve as a carriage for power driven mechanism for swinging the rollers *g*, *g'*. This mechanism comprises a reversible electric motor 91, to the shaft of which a pinion 92 is secured, which is adapted to 40 drive a variable speed transmission 93 in a housing 94 on said frame; a shaft 95 driven by said transmission gearing, a bevelled pinion 96 fixed to shaft 95, an internally toothed bevelled wheel 97 fixed to a shaft 98 45 which is mounted in bearings 99 in the casing 82; a worm 100 on shaft 98 and meshing with teeth 101 fixed to the periphery of arcuate slide 81. By operating the motor 91, the shaft 98 will be driven to swing slide 81 50 and the shaping rolls *g*, *g'*. This power mechanism facilitates the work and furthermore makes it possible to shift the shaping rolls at a regular and regulated speed.

The frame 90 and the parts carried thereby, including the motor 91, the shaping rolls and the gearing for swinging them, is movable longitudinally of the pipe, so that the shaping rolls can be shifted into and out of operative relation with the end of the pipe 55 and is movable transversely so that said rolls may be shifted transversely to separate them from the formed flange and also so that the shaping mechanism can be shifted transversely out of the way, so that pipe may be 60 loaded and unloaded into the machine. For

this purpose, frame 90 is guided and longitudinally slideable in ways 102 in a carriage 103 transversely, and guided in ways 104 formed in a frame 105 which is fixedly supported on the base of the machine. A 70 screw 106, journalled in bearings 107 in carriage 103, is threaded to a nut or runner 108, which is non-rotatably held between depending lugs 109 on the frame 90 and a hand wheel 110 is fixed to shaft 108 at the 75 front end of carriage 103. By rotating said hand-wheel, the frame 90, with the shaping rolls and mechanism for operating them, may be moved longitudinally to shift the rolls into operative relation with the end of 80 the pipe. Power driven mechanism for operating the carriage 103 transversely to move the shaping mechanism to one side of the pipe after the latter has been shaped to permit the pipe to be removed from the 85 lugs and for reversely shifting said mechanism after a pipe has been placed in operative position on the lugs, comprises an electric motor 111 fixed to the top of carriage 90; a pinion 112 on the motor shaft, a gear-wheel 113 meshing with pinion 112, a transverse screw-shaft 114 carried in bearings 115 and 116 on carriage 103 and operatively connected to a non-rotatable nut 117, which is confined against longitudinal movement 95 with the screw by lugs 118 on frame 105. To shift the carriage 103 and the parts carried thereby transversely, it is only necessary to switch on the motor according to the 100 direction in which the carriage is to be shifted. This exemplifies power operated mechanism for quickly shifting the shaping mechanism transversely into and out of its operative position. For convenience of the operator, a platform 119 is provided at the 105 front end of the machine and this is suspended from carriage 103 so that it will be transversely adjusted with the carriage 103. The operation is as follows: Normally, the 110 shaping rolls and carriage will be disposed to one side of the drive-shaft *e* so that a suitable truck, adapted to run on rails 44, and carrying a length of pipe to be shaped, may be run into position to deliver the pipe where it can be pushed backwardly between 115 rolls *a* and into the chuck *c*. The jaws 23 of chuck *c* are then tightened and rollers *a* will be adjusted by the operation of motor 78 and the intermediate gearing, so that the rollers will engage and support the front 120 end of the pipe. Fluid under pressure will then be admitted to cylinder 34 to operate shaft 32 and expand the jaws of chuck *b*, so that the pipe will be internally gripped adjacent the rolls *a*. As well understood in 125 the art, the pipe to be flanged is usually heated where it is to be shaped and, therefore, it is important that the front end of the pipe be supported and gripped so as to avoid undesirable deformation of the pipe. 130

4 Power will then be applied to gear 36 on shaft *e* and the latter, through external chuck *c* and internal chuck *b*, will rotate the pipe. After the pipe has been gripped and placed in its operative position, the carriage 103 will be shifted transversely by the operation of motor 111 to bring rolls *g*, *g'* into alignment with one side of the pipe. The hand-wheel 110 will then be operated to shift the frame 90 longitudinally to bring the rolls *g*, *g'* into operative relation with respect to the end of the pipe, as shown in Fig. 8. Motor 91 will then be operated to swing slide 81 in the casing 82 while the pipe is in rotation to form the flange on the front end of the pipe, as shown in Fig. 10. When this shaping operation has been completed, rolls *g*, *g'* will be disengaged from the pipe flange and the carriage 103 will be operated transversely until it is located at one side of the pipe, so that the latter may be withdrawn from the chucks and shaft *e* and thereupon the machine will be again operated as before, it being understood that the rolls *g*, *g'* will be swung reversely, so that they may be brought into operative engagement with the pipe end by the longitudinal rearward shift of the frame.

30 The invention exemplifies a machine in which the pipe is held by an internal chuck and externally supported by rollers at the end where the shaping is done, so that irregular deformation of the pipe is prevented and the shaping is localized to the desired point; also a machine in which the internal chuck is operated by a pipe which extends rearwardly and is driven at its rear end; also one in which the chucks at both ends of the pipe are driven in unison to avoid deformation of the pipe; also one in which the chuck, which is remote from the shaping mechanism, is quickly and longitudinally adjustable by power to adapt the machine for pipes of different lengths; also one in which the rolls for supporting the outside of the pipe adjacent the end being shaped are quickly adjustable by power driven mechanism; also one in which the carriage, on which the shaping mechanism is mounted, may be quickly operated by power into and out of its operative position in front of the pipe; also one in which the internal chuck may be adjusted longitudinally relatively to the supporting rollers at the end of the pipe to be shaped, so that the chuck and rollers may be coactively arranged as desired for different shaping operations, such as forming flanges of different lengths or for otherwise shaping the end of the pipe.

35 The invention is not to be understood as restricted to the details set forth, since these may be modified within the scope of the appended claims, without departing from the spirit and scope of the invention.

60 Having thus described the invention, what

I claim as new and desire to secure by Letters Patent, is:

1. In a machine for shaping pipe, the combination of shaping mechanism, means for externally supporting one end of a pipe adjacent the shaping mechanism, means adjacent the supporting means for engaging substantially the entire inner periphery of the said one end of the pipe, and means for supporting the other end of the pipe. 75

2. In a machine for shaping pipe, the combination of shaping mechanism, stationary means for externally supporting one end of a pipe adjacent the shaping mechanism, rotatable means adjacent the supporting means for internally gripping the said one end of the pipe, rotatable means for gripping the other end of the pipe, and mechanism for rotating both rotatable means to rotate the pipe. 80

3. In a machine for shaping pipe, the combination of shaping mechanism, means for externally supporting one end of a pipe adjacent the shaping mechanism, a rotatable chuck adjacent said external supporting means for internally gripping the said one end of the pipe, a rotatable chuck for gripping the other end of the pipe, and means for rotating the chucks to rotate the pipe. 85

4. In a machine for shaping pipe, the combination of shaping mechanism, a chuck for internally gripping a pipe adjacent the end thereof which is adjacent the shaping mechanism, means for externally supporting the pipe adjacent the chuck, means for supporting the other end of the pipe, and means coaxial with and extending through said other end of the pipe for operating said chuck. 95

5. In a machine for shaping pipe, the combination of shaping mechanism, a chuck for internally gripping and supporting one end of a pipe adjacent the shaping mechanism, means for externally supporting the pipe adjacent the chuck, means for supporting the other end of the pipe, a shaft extending through the pipe and to which the chuck is fixed, and means for rotating the shaft. 105

6. In a machine for shaping pipe, the combination of shaping mechanism, a chuck for internally gripping and supporting one end of a pipe adjacent the shaping mechanism, means for externally supporting the pipe adjacent said chuck, a chuck for gripping the other end of the pipe, a rotatable shaft extending from the internal chuck through said other end of the pipe and to which both of the chucks are fixed, and means for rotating said shaft. 115

7. In a machine for shaping pipe, the combination of shaping mechanism, a chuck for internally gripping and supporting one end of a pipe adjacent the shaping mechanism, means for externally supporting the pipe adjacent said chuck, a chuck for gripping the other end of the pipe, means for longitudi- 125

nally adjusting said last mentioned chuck relatively to the other, to hold pipes of different lengths, a shaft extending from the internal chuck through said other end of the pipe and to which both of the chucks are connected to be driven, and means for rotating the shaft.

8. In a machine for shaping pipe, the combination of shaping mechanism, a rotatable 10 chuck for internally gripping a pipe adjacent the end thereof which is adjacent to the shaping mechanism, a rotatable chuck for supporting the pipe adjacent the other end of the pipe, a shaft disposed in said pipe 15 between the chucks, and extending beyond said other end of the pipe and means at said extended portion of the shaft for driving said shaft.

9. In a machine for shaping pipe, the combination of shaping mechanism, a rotatable 20 chuck for internally gripping a pipe adjacent the end thereof which is adjacent to the shaping mechanism, a rotatable chuck for supporting the pipe adjacent the other end 25 of the pipe, means for adjusting one of the chucks longitudinally relatively to the other, to hold pipes of different lengths, a shaft between the chucks extended beyond said other pipe end, and means at said extended 30 portion of the shaft for driving the shaft.

10. In a machine for shaping pipe, the combination of shaping mechanism, a chuck for internally gripping a pipe adjacent the end thereof which is adjacent to the shaping 35 mechanism, a chuck for gripping the pipe adjacent its other end, a drive shaft extending into said other pipe end and fixed to the internal chuck, and a longitudinally adjustable carriage for the chuck at said other pipe end.

11. In a machine for shaping pipe, the combination of shaping mechanism, means for internally supporting one end of a pipe adjacent the shaping mechanism, means for 45 supporting the other end of the pipe, the supporting means being supported so the pipe can be placed in operative position from the end at which the shaping mechanism is located, and a pivotally sustained 50 shaft connected to said internal support.

12. In a machine for shaping pipe, the combination of shaping mechanism, means for internally supporting one end of a pipe adjacent the shaping mechanism, means for 55 externally supporting the pipe adjacent the internal supporting means, means for supporting the other end of the pipe, the supporting means permitting the pipe to be placed in operative position from the end at 60 which the shaping mechanism is located, and a pivotally sustained shaft connected to said internal means.

13. In a machine for shaping pipe, the combination of shaping mechanism, an internal chuck for the pipe adjacent the end 65

thereof which is adjacent the shaping mechanism, a chuck for supporting the other end of the pipe, a shaft for the internal chuck extending through said other end of the pipe, means for driving said shaft, and means for operating the internal chuck extending through said shaft and disposed at the end thereof which is remote from the shaping mechanism.

14. In a machine for shaping pipe, the combination of shaping mechanism, means for externally supporting one end of a pipe adjacent the shaping mechanism, an internal chuck adjacent said external supporting mechanism, a chuck to grip the other end of the pipe, and means for driving both of said 75 chucks comprising a shaft extending from the internal chuck through the chuck at said other end of the pipe, and connected to drive both chucks.

15. In a machine for shaping pipe, the combination of shaping mechanism, means for externally supporting one end of a pipe adjacent the shaping mechanism, an internal chuck adjacent said external supporting 80 mechanism, a chuck to grip the other end of the pipe, a longitudinally adjustable carriage for the latter chuck, and means for driving both of said chucks comprising a shaft extending from the internal chuck 85 through the chuck at said other end of the pipe.

16. In a machine for shaping pipe, the combination of shaping mechanism, means for externally supporting one end of a pipe adjacent the shaping mechanism, an internal chuck adjacent said external supporting 90 mechanism, a chuck to grip the other end of the pipe, a longitudinally adjustable carriage for the latter chuck, means for driving both of said chucks comprising a shaft 95 extending from the internal chuck through the chuck at said other end of the pipe, and a support for the shaft beyond the carriage.

17. In a machine for shaping pipe, the combination of shaping mechanism, an internal chuck for gripping and supporting one end of a pipe adjacent the shaping mechanism, an external support for the pipe adjacent the shaping mechanism, a chuck 100 for gripping the pipe at its other end, a shaft fixed to the internal chuck and extending through and having a sliding connection with the chuck at said other end, and mechanism for driving said shaft.

18. In a machine for shaping pipe, the combination of shaping mechanism, means for supporting one end of a pipe adjacent said mechanism, a longitudinally adjustable carriage provided with an adjustable chuck 110 for supporting the other end of the pipe, a drive shaft for the chuck having a slideable connection therewith, mechanism for longitudinally adjusting said carriage so that the machine may be adapted for different 115 120 125 130

lengths of pipe without adjusting the supporting means adjacent the shaping mechanism.

19. In a machine for shaping pipe, the combination of shaping mechanism, a chuck for internally supporting one end of a pipe adjacent said mechanism, a longitudinally adjustable carriage, a chuck for gripping the other end of the pipe movable with the carriage, mechanism for longitudinally adjusting said carriage so that the machine may be adapted for different lengths of pipe without adjusting the supporting means adjacent the shaping mechanism, and a drive-shaft fixed to the internal chuck and slidably connected to the chuck.

20. In a machine for shaping pipe, the combination of shaping mechanism, means for supporting one end of a pipe adjacent said mechanism, a longitudinally adjustable carriage, means movable with the carriage for supporting the other end of the pipe, and mechanism for longitudinally adjusting said carriage relatively to the supporting mechanism adjacent the shaping mechanism so that the machine may be adapted for different lengths of pipe, comprising a motor mounted on and movable with the carriage.

21. In a machine for shaping pipe, the combination of shaping mechanism, means for supporting one end of a pipe adjacent said mechanism, a longitudinally adjustable carriage, means mounted on and movable with the carriage for supporting the other end of the pipe, mechanism for longitudinally adjusting said carriage relatively to the supporting mechanism adjacent the shaping mechanism, comprising a motor and gearing mounted on and movable with the carriage, and a drive-shaft fixed to the supporting means adjacent the shaping mechanism and to which the other supporting means is slidably adjustable.

22. In a machine for shaping pipe, the combination of shaping mechanism, stationary means for externally supporting one end of a pipe adjacent the shaping mechanism comprising a plurality of rollers, devices for radially adjusting the rollers, and means for conjointly operating said devices, and means for supporting the other end of the pipe.

23. In a machine for shaping pipe, the combination of shaping mechanism, stationary means for externally supporting one end of a pipe adjacent the shaping mechanism comprising a plurality of rollers, devices for radially adjusting the rollers, and means for conjointly operating said devices, means for supporting the other end of the pipe, and means for rotating the pipe.

24. In a machine for shaping pipe, the combination of shaping mechanism, means for externally supporting one end of a pipe adjacent the shaping mechanism comprising

a series of rollers for engaging the external periphery of the pipe, mechanism comprising a motor and gearing for conjointly and radially adjusting the rollers, means for supporting the other end of the pipe, and means for rotating the pipe.

25. In a machine for shaping pipe, the combination of shaping mechanism, means for externally supporting one end of the pipe comprising a series of rollers for engaging the external periphery of the pipe, mechanism for conjointly and radially adjusting the rollers comprising radially extending screw-shafts and connecting shafts between and geared to the radial shafts, means for supporting the other end of the pipe, and means for rotating the pipe.

26. In a machine for shaping pipe, the combination of a shaping mechanism, mechanism for externally supporting one end of a pipe adjacent the shaping mechanism comprising a series of rollers for engaging the external periphery of the pipe, a stationary frame in which said mechanism is supported, mechanism for conjointly and radially adjusting the rollers comprising a motor mounted on said frame, means for supporting the other end of the pipe, and means for rotating the pipe.

27. In a machine for shaping pipe, the combination of shaping mechanism, a chuck for internally gripping a pipe adjacent the end thereof which is adjacent to the shaping mechanism, means for supporting the pipe at its other end, and a shaft for the chuck endwise movable to shift the latter longitudinally relatively to the supporting means.

28. In a machine for shaping pipe, the combination of shaping mechanism, means for internally supporting a pipe adjacent the end thereof which is adjacent to the shaping mechanism, means for externally supporting the pipe adjacent the internal support, means for supporting the other end of the pipe, and a shaft for the internal support endwise movable to shift the internal support longitudinally relatively to the external support.

29. In a machine for shaping pipe, the combination of shaping mechanism, means for internally supporting a pipe adjacent the end thereof which is adjacent to the shaping mechanism, means for supporting the other end of the pipe, a shaft for the internal support, movable endwise to shift the internal support longitudinally relatively to the external support, and means for driving said shaft.

30. In a machine for shaping pipe, the combination of shaping mechanism, an internal chuck for a pipe adjacent the end thereof which is adjacent to the shaping mechanism, means for externally engaging the pipe adjacent the internal support, a chuck for holding the other end of the pipe,

an endwise movable shaft for the internal chuck, to shift it longitudinally relatively to the external support, and means for driving said shaft from said other end of the pipe.

31. In a machine for shaping pipe, the combination of shaping mechanism, supports for both ends of the pipe, a transversely adjustable carriage on which the shaping mechanism is mounted, the supports permitting a pipe to be placed in position to be operated on from the end at which the shaping mechanism is located, and power driven means for transversely shifting said carriage.

32. In a machine for shaping pipe, the combination of shaping mechanism, means for supporting the pipe at both of its ends, a transversely adjustable carriage, a longitudinally adjustable carriage for the shaping mechanism mounted on the transversely adjustable carriage, the supporting mechanism permitting a pipe to be placed in position to be operated on from the end at which the shaping mechanism is located, and power driven means for shifting said transversely movable carriage.

33. In mechanism for shaping pipe, the combination of shaping mechanism, supports for both ends of a pipe, a swinging carriage for said mechanism, and mechanism for swinging the carriage comprising a motor.

34. In mechanism for shaping pipe, the combination of swinging shaping mechanism, supports for both ends of a pipe, a transversely and longitudinally adjustable carriage on which said swinging mechanism is mounted, and mechanism for swinging the shaping mechanism comprising a motor and gear mounted on the carriage.

35. In a machine for shaping pipe, the combination of shaping mechanism, an internal chuck for supporting one end of a pipe, adjacent the shaping mechanism, a longitudinally adjustable chuck at the other end of and for supporting the pipe, a hollow shaft fixed to the internal chuck extending through said other end of the pipe, a gear fixed to said shaft at the end remote from

the internal chuck, and mechanism for operating the internal chuck comprising a rod extending through said shaft.

36. In a machine for shaping pipe, the combination of shaping mechanism, an internal chuck for supporting one end of a pipe, adjacent the shaping mechanism, a chuck at the other end of the pipe for supporting it, a hollow shaft fixed to the internal chuck and extending through said other end of the pipe, a gear for driving and fixed to said shaft, and mechanism for operating the internal chuck rotatable with said shaft.

37. In a machine for shaping pipe, the combination of shaping means, supports for both ends of the pipe, a transversely adjustable carriage on which the shaping means is mounted, power driven means for transversely shifting said carriage, and an operator's platform mounted on said carriage.

38. In a machine for shaping pipe, the combination of shaping mechanism, supporting devices for the ends of the pipe respectively, a shaft extending into the pipe, means for driving the shaft, and a slidable driving connection between the shaft and one of the supporting devices, the pipe being rotatable by the device which is slidably connected to the shaft.

39. In a machine for shaping pipe, the combination of shaping mechanism, means for externally supporting one end of a pipe adjacent the shaping mechanism, a chuck adjacent said supporting means for internally gripping the said one end of the pipe, and means for supporting the other end of the pipe.

40. In a machine for shaping pipe, the combination of shaping mechanism, means for externally supporting one end of a pipe adjacent the shaping mechanism, a chuck adjacent the external supporting means for internally gripping the said one end of the pipe, means for supporting the other end of the pipe, and means for rotating the chuck to rotate the pipe.

Signed at Chicago, Illinois, this 2nd day of March, 1925.

JAMES HALL TAYLOR.
